UNITED STATES PATENT OFFICE

MAGNUS E. WIDELL, OF CINCINNATI, OHIO, ASSIGNOR TO AMERICAN CAN COMPANY,
OF NEW YORK, N. Y., A CORPORATION OF NEW JERSEY

INTERIOR COLLAR CAN

Application filed May 4, 1923. Serial No. 636,519.

The present invention relates to cans of the interior collar type in which the material of the body is adapted to be severed beneath the top and the cover thereafter used as a temporary closure fitting upon a separate collar secured within the upper part of the body.

A principal object of the invention is the provision of a construction of this character in which the collar may be secured in place in such manner as to prevent the leakage of liquids between the same and the can body, and this without the use of solder, or any other separate sealing medium.

A further object is the provision of a method of assembling collar bands and can bodies, which, through very simple operations, produces a relationship between the parts attaining the foregoing result.

A further object is the provision of an improved body construction, which facilitates the formative operations and increases the efficiency of the resultant structure.

Other objects and advantages of the invention will be apparent as it is better understood from the following description, which, taken in connection with the accompanying drawings, discloses a preferred embodiment thereof.

Referring to the drawings,

Figure 1 is a side elevation, partially broken away, of a container embodying the principles of my invention;

Figs. 2, 3 and 4 are detail sectional views showing the parts in the positions assumed at the different stages of the assembling operation; and

Fig. 5 is a detail plan view of a part of the body blank.

The container as thus illustrated, comprises a body 21, to which is permanently secured a bottom end 22 and a top 23, which latter, in the present instance, is of the depressed head or plug variety. Said body is provided with parallel score lines 24 and 25, the latter of which is disposed immediately beneath a seam 26 by which the cover is secured to the body. These score lines set off a tearing strip provided at one end with a tongue 27, which is adapted to be engaged by a key, or otherwise, for removal of the

strip. Diagonal score lines 28 are provided between the parallel lines 24 and 25 and serve to direct the tear back to said lines, in the event it is deflected therefrom. A separate collar member 29 is positioned within the body, in accordance with the method of my invention, and extends from a point slightly above the upper score line 25 to a point considerably below the lower line 24. Said collar, in the present instance, is formed with tight beads, or false wire edges, 31 and 32 at both the top and bottom, the former of which provides a shoulder within which the cover may be fitted after severance, and the latter of which is adapted to be expanded into locking engagement with the container body, as will now be described.

As shown, the bead 32 is substantially solid and, when acted upon by an interior expanding die, is forced against the body 21 with such pressure as to expand the latter and form a groove 33 extending entirely around the circumference of the can. By this same operation, the bead 32 is, of course, bent outwardly from the position shown in Fig. 2 to that shown in Fig. 3, in which it tightly engages within the groove 33.

After the parts are brought to the position shown in Fig. 3, the bead may be set up to the position shown in Fig. 4 by means of 80 clenching dies, or other suitable apparatus, acting upon the exterior of the bead 34, which results from the formation of the groove 33, as heretofore described. The clenching dies may operate close to the body of the can 85 and form definite shoulders 35 pressed against and holding the bead 32 at the top and bottom. This increases the efficiency of the structure by further tightening the joint between the collar 29 and the can body 21, and I have found that this joint effectively prevents the leakage of liquid between these parts.

My invention comprises the beading of a double thickness of the sheet metal of the collar member into the wall of the container 90 body, thereby greatly stiffening the collar and also the body against distortion, and holding the collar more tightly and firmly in the body, as best seen in Figs. 3 and 4.

Figure 5 illustrates in detail the form of

the body blank which I prefer to employ in the construction of my container. The blank edges, throughout the greater portion of their length, are interfolded in a side seam of the lock type, indicated by the reference character 36. The overlapping edge, however, is cut-away, as indicated at 37 and, in the area of the bead 34, is merely lapped over the opposing edge, as shown at 37', in Fig. 1. This facilitates the bending of the metal at this point, which would be very difficult with the thicknesses necessary for a lock seam. An auxiliary lock portion 40 is provided above the cut-away part 37 beneath the tearing strip. It will be understood that the portion of the body above said strip is practically all interfolded in the double seam 26 and, therefore, a lock seam in this area is unnecessary.

The cover is seamed onto an upper body flange 38, in the usual manner, and is provided inwardly of the seam with a shoulder 39, resting upon the top of the collar bead 31, a vertical wall part 41 being provided about a head portion 42 and being adapted to be inserted within the upper end of the container in frictional engagement with the bead 31. With this construction, the cover may be used as a temporary friction plug closure, after removal of the tearing strip.

It will be understood that my invention is not limited to use in a container having a body of cylindrical shape, but the body of the container may be of other shapes such as rectangular, polygonal, oval, etc.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. A container, comprising a body having an end member permanently secured thereto and adapted to be opened by severance beneath said member, and a separate collar positioned within the upper part of said body and adapted to receive said end member as a temporary closure after severance from the body, said collar being provided with a bead, or wire edge, expanded into liquid-tight locking engagement with the body and by its expansion forming a groove in the inner face of the body.

2. A container, comprising a body having an end member permanently secured thereto and adapted to be opened by severance beneath said member, and a separate collar positioned within the upper part of said body and adapted to receive said end member as a temporary closure after severance from the body, said collar being provided with a rigid

curled bead forced against the interior of the body whereby a retaining groove is formed in the inner face of said body in which said bead is disposed in liquid-tight sealing relationship and with a tight joint.

3. The method of assembling separate collar members within can bodies, which consists in positioning a collar member, provided with a rigid curled edge, within the body and expanding said bead, or edge, from within to form a groove in the inner face of said body in which the bead is disposed in liquid-tight sealing engagement.

4. A container, comprising a body having an end member permanently double seamed thereto and adapted to be opened by severance of the body beneath said member, a separate collar positioned and held within the upper part of said body and formed at its upper end with a friction closure seat, said end closure being formed with a friction plug closure seated in said friction seat of the collar and removable after the severance of the body and afterwards replaceable as a friction closure, and said collar being formed at its lower end with a ring pressed outward into said body so as to form an outwardly projecting bead in the otherwise cylindrical surface of the body.

5. A method of making can bodies which consists in forming a body blank into cylindrical body shape with the ends of the blank attached together, and forming a corresponding collar therefor curled to form beads along its upper and lower edges and of a size to fit within said body, inserting said collar within the body and then applying internal pressure against the lower of said curls and opposing resistance on the outside of the can body at the sides of the curl to form a peripheral recess within the body and to seat the collar securely therein with a tight joint between said parts.

6. The combination of a container body of sheet metal formed with an interior cylindrical surface, and a sheet metal collar having a substantially cylindrical bead the upper and lower portions of which form two thicknecesses of metal and said bead being pressed tightly into the interior of the cylindrical surface of the body and thereby forming a bead on the body and a tight joint between said beads.
